UNITED STATES PATENT OFFICE.

HARRISON BRUNER, OF SUNDANCE, WYOMING.

DESIGN FOR A BADGE.

SPECIFICATION forming part of Design No. 22,716, dated August 22, 1893.

Application filed July 5, 1893. Serial No. 479,660. Term of patent 14 years.

To all whom it may concern:

Be it known that I, HARRISON BRUNER, a citizen of the United States, residing at Sundance, in the county of Crook, State of Wyoming, have invented a certain new Design for a Badge, of which the following is a specification, reference being had therein to the accompanying drawing.

The leading feature of my design consists in a double heart-shaped outline with plates connected therewith by chain-like connections.

A represents the double-heart-shaped body and B a plurality of plates of octagonal form,

said plates being pendent from the portion A 15 by chain-like connections C. A double plate D, dotted lines, may be provided. The plates are designed to receive suitable inscriptions.

What I claim as new is—

The design for a family badge substantially 20 as herein shown and described.

In testimony whereof I affix my signature in presence of two witnesses.

HARRISON BRUNER.
